Design No. 2,709, dated July 23, 1867.

DESIGN FOR A MIRROR-FRAME.

The Schedule referred to in these Letters Patent and making part of the same.

TO ALL WHOM IT MAY CONCERN:

Be it known that I, RUSSEL FRISBIE, of the town of Cromwell, county of Middlesex, and State of Connecticut, have originated and designed a new Pattern for Mirror-Frames and Standards, of which the following is a full, clear, and exact description, reference being had to the accompanying drawings, making part of this specification.

The design consists of a half-oval frame, made of any suitable material, held by two upright arms, joined together at the bottom, and fastened to a fancy carved base.

What I claim as my invention, and desire to secure by Letters Patent, is—

The design or pattern for mirror-frames and standards, as shown and described.
